UNITED STATES PATENT OFFICE.

DAVID KARGER, OF MILWAUKEE, WISCONSIN.

DESIGN FOR A SPAT.

Application filed September 4, 1923. Serial No. 7,146. Term of patent 14 years.

To all whom it may concern:

Be it known that I, DAVID KARGER, a citizen of the United States, residing at Milwaukee, in the county of Milwaukee and State of Wisconsin, have invented a new, original, and ornamental Design for a Spat, of which the following is a specification, reference being had to the accompanying drawing, forming part thereof.

The figure is a perspective view of a spat showing my new design.

I claim:

The ornamental design for a spat as shown.

In witness whereof, I hereto subscribe my name this 31st day of August, 1923.

DAVID KARGER.
